UNITED STATES PATENT OFFICE.

HARRY L. SCHROEDER, OF ASPINWALL, IOWA.

DESIGN FOR A HOLDER FOR TOILET ARTICLES.

Application filed June 7, 1923. Serial No. 6,438. Term of patent 7 years.

To all whom it may concern:

Be it known that I, HARRY L. SCHROEDER, a citizen of the United States of America, residing at Aspinwall, in the county of Crawford and State of Iowa, have invented a new, original, and ornamental Design for a Holder for Toilet Articles, of which the following is a specification, reference being had to the accompanying drawing, forming a part hereof.

The drawing is a perspective view of a holder for toilet articles showing my design.

I claim:

The ornamental design for a holder for toilet articles, as shown.
